UNITED STATES PATENT OFFICE.

FRANCIS HODGKINSON, OF SWARTHMORE, PENNSYLVANIA, ASSIGNOR TO WESTINGHOUSE ELECTRIC & MANUFACTURING COMPANY, A CORPORATION OF PENNSYLVANIA.

TURBINE-BLADE BRACING.

Application filed May 22, 1925. Serial No. 32,151.

My invention relates to elastic fluid turbines, more particularly to the blading thereof, and has for its object the provision of an efficient bracing for the blades which shall be easy to apply, offer a minimum of resistance to the flow of elastic fluid through the turbine, establish a sturdy, unitary blading structure and which shall minimize vibration of the blades.

10 Apparatus embodying features of my invention is illustrated in the accompanying drawings forming a part of this specification, in which Fig. 1 is a fragmentary plan view of a turbine blade carrying element, either moving or stationary, with a plurality of blades mounted thereon, said blades being provided with my improved blade bracing; Fig. 2 is a sectional view 15 across a bracing member taken along the line II-II of Fig. 1; Fig. 3 is a vertical sectional view of the blading shown in Fig. 1 along the line III-III thereof and showing the blades mounted upon a fragment of a turbine rotor; Fig. 4 is a detached plan 20 view of the lashing members, and Fig. 5 shows a perspective view of a modified form of my invention.

As is well known in the art to which my invention relates, turbine blades, in operation, are subjected to various shocks and strains which tend to cause vibration. It has been found necessary therefore to provide some form of bracing means in order to minimize vibration of the blades. Various forms of blade lashing have been proposed, that more commonly used being in the form of a lashing wire which is threaded through holes in the blades and secured to the blades either by deforming the wire 30 where it passes through the blade or by soldering or brazing the wire to the blade where it passes through the hole. Difficulties have been encountered in securing a lashing wire to a blade by deformation of the wire due to the fact that a thorough 35 mechanical connection is hard to obtain by such means. On the other hand, brazing or soldering the lashing wire to the blades tends to injure the physical properties of the blades and thus weakens them.

In accordance with my invention, I pro-

vide a bracing comprised of individual bracing members secured to the front and back of adjacent blades in a row, and join the individual members together at a point intermediate the blades. The individual members are cut from bars of metal of stream line cross section in the direction of motive fluid flow and are each provided with one or more tenons adapted to pass 55 through suitable holes in the blades and are riveted before assembly in the blade holding element. The individual members may be joined together between the blades by fusion of metal, preferably welding. The welding 60 operation, being carried out at a point remote from the blades, does not materially heat the blades and thus has no deleterious effect upon the physical properties of the blades.

Individual members are secured to the front and back of a blade in staggered relation, thus bracing the blade at two points of its length for each row of lashing and further minimizing the vibration of the 70 blade.

Referring now to the drawings for a better understanding of my invention, I show in Fig. 1 at 10 a fragment of the blade carrying element having a plurality 80 of blades 11 mounted thereon, said blades being provided with my improved bracing means. The bracing which is applied between adjacent blades in a row is comprised of two members 12 and 13 so cut that when 85 each is riveted to its associated blade and the two joined together they form a member rigidly securing the one blade to the other. The form in which the members are cut is best seen by reference to Figs. 4 90 and 5.

The inner end, or end adjacent the blades, of each of the lashing members 12 and 13 is cut to conform to the contour of the blade to which it is attached. Each of 95 the pieces 12 and 13 is provided with one or more tenons 15 and 16 adapted to pass through complementary holes 17 and 18 formed in the blades 11. The outer ends of each of the members 12 and 13, or ends 100 remote from the blading, are beveled as shown at 19 and 21 in Figs. 3 and 4 to pro-

vide a better means for joining the edges upon assembly by fusion of metal, such as by soldering, brazing or welding. The bracing members 12 and 13 are stream line in cross section as shown in Fig. 2 so as to offer the minimum resistance to flow of the motive fluid therethrough.

In assembling the blading structure, the members 12 and 13 are fitted to the blades 10 and the ends of the tenons 15 and 16 riveted, thus firmly securing the members to the blades. Holes 17 and holes 18 are provided in each of the blades, one set below the other, so that members 12 and 13 for each 15 blade are in staggered relation to each other. The blades are then assembled in the blade holding element and adjacent ends of the elements 12 and 13 are joined together by welding or other similar process, thus forming 20 a unitary structure of the whole.

As is well understood, blade lashing is usually applied to segments of blades around the blade carrying element in order 25 to avoid difficulties due to unequal expansion and contraction of the parts. In Fig. 3 I show, for the purpose of illustration, a segment of four blades thus united, though the number of blades in a segment will depend entirely upon their physical characteristics 30 and the service to which they are subjected. It will be clearly understood from the drawing that by carrying out the welding process employed in joining the individual lashing members together remotely 35 from the blades, the heat thereof does not affect the physical properties of the blades. It may be further seen that the staggered relation of the lashing members, as applied to a blade, permits an expansion thereof between the blades without danger of crushing 40 or weakening the material of which the lashing members is composed.

Referring to Fig. 5 I show a modified form of my invention wherein the bracing member 12 is provided with only one tenon, 45 21. The tenon 21 is made angular in cross-section and is adapted to fit into a hole of similar contour formed in the blade. The purpose of the angular formation of the tenon 21 is to prevent the bracing member 50 12 from turning after assembly in the turbine.

From the foregoing, it will be apparent that I have invented an improved bracing 55 means for turbine blades which offers a minimum of resistance to the flow of motive fluid through the blades, which is easy of assembly, which may be assembled without affecting the physical properties of the 60 blades, and which provides a sturdy unitary blade structure.

While I have shown my invention in but 65 two forms, it will be obvious to those skilled in the art that it is not so limited, but is susceptible of various other changes and

modifications, without departing from the spirit thereof, and I desire, therefore, that only such limitations shall be placed thereupon as are imposed by the prior art or as are specifically set forth in the appended 70 claims.

What I claim is:

1. A turbine blade bracing means comprising a plurality of bracing members disposed between adjacent blades, said bracing members being secured to the adjacent blades and joined to each other intermediate 75 said adjacent blades.

2. In a turbine, a plurality of blades in a row, a bracing member secured to each 80 of the blades and joined to the bracing member of an adjacent blade by fusion of metal intermediate said adjacent blades.

3. In a turbine, a plurality of blades in a row, a bracing member secured to the 85 front and a bracing member secured to the back of each of the blades, each of said bracing members being secured to the bracing member of an adjacent blade at a point intermediate the adjacent blades. 90

4. In a turbine, a plurality of blades in a row, a bracing member secured to the front and a bracing member secured to the back of each of the blades in staggered relation, 95 each of said bracing members being secured to the bracing member of an adjacent blade at a point intermediate the adjacent blades by fusion of metal.

5. In a turbine, a blade carrying element, a blade mounted in said element, a bracing member for the blade, said bracing member comprising a strip of metal of stream line 100 cross section having one or more tenons thereon for riveting to the blade and joined to an adjacent bracing member by fusion 105 of metal.

6. In a turbine, a blade carrying element, a blade mounted in said element, a bracing member for the blade, said bracing member comprising a strip of metal of stream line 110 cross section having one or more tenons thereon for riveting to the blade and having its outer end bevelled and joined to an adjacent bracing member by fusion of metal.

7. In a turbine, a blade carrying element, a blade mounted thereon, a pair of bracing members for the blade extending across the front and back thereof in offset relation, each of said bracing members comprising a piece of metal of stream line cross section 115 in the direction of motive fluid flow and cut to conform to the contour of the blade, holes provided in the blade, tenons provided on the bracing members and fitting into the holes for riveting to the blade, said pieces of metal being bevelled at their outer ends for joining to an adjacent bracing member. 120

8. In a turbine, a plurality of blades in a row, a member secured to the front face and a member secured to the back face of each 125 130

of the blades and adjacent members being joined intermediately of the spaces between blades.

9. In a turbine, a plurality of blades in a row, a member secured to the front face and a member secured to the back face of each of the blades in offset relation and

adjacent members being welded together intermediately of the spaces between blades.

In testimony whereof, I have hereunto 10
subscribed my name this 29th day of April,
1925.

FRANCIS HODGKINSON.
